CLAIM

We claim the ornamental design for a scissors sharpening device, as shown and described.

DESCRIPTION

FIG. 1 is a perspective view of an embodiment of a scissors sharpening device of the present invention;

FIG. 2 is a top plan view thereof;

FIG. 3 is a bottom plan view thereof;

FIG. 4 is a left-side elevational view thereof;

FIG. 5 is a right-side elevational view thereof;

FIG. 6 is a front elevational view thereof; and,

FIG. 7 is a rear elevational view thereof.

The broken lines shown in the drawings illustrate portions of the scissors sharpening device that form no part of the claim.
